UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

PAPER-FEEDING DEVICE.

1,317,509.

Specification of Letters Patent. Patented Sept. 30, 1919.

Original application filed March 28, 1917, Serial No. 158,142. Divided and this application filed April 3, 1918. Serial No. 226,494.

To all whom it may concern:

Be it known that I, WILLIAM W. LASKER, a citizen of the United States, residing in Brooklyn, in the county of Kings and State 5 of New York, have invented certain new and useful Improvements in Paper-Feeding Devices, of which the following is a specification.

This invention relates to a printing tabulator of the kind adapted to be controlled by perforated cards, and relates more particularly to matter divided from my copending application Serial No. 158,142 filed March 28, 1917, for printing tabulators.

15 The invention herein described relates particularly to the paper feeding mechanism of the printing carriage of said printing tabulator; and, therefore, only as much of the printing tabulator is described herein 20 as is necessary to show the connection between the matter of the original application and the matter divided out and described herein.

While herein and in said application minute details of one of many possible embodiments of the invention are described, the invention is not limited to these since various changes may be made in the details of construction and combination without departing from the spirit and scope of the invention as claimed.

One object of the invention is to improve generally apparatus of this kind.

Another object is to provide an improved 35 method of feeding, supporting clamping and releasing the paper and of adjusting the amount of feed of the paper.

Another object is to provide efficient means for preventing overthrow of the feeding when the machine is running at high- 40 speed.

Another object is to provide a new and improved method of mounting the paper supporting rolls.

45 Another object is to provide an economical and efficient platen for pressing the paper against the type.

Still further objects and advantages of the present improvement will be set forth in the 50 following description and drawings in which,

Figure 1 is a side elevation of the printing and calculating mechanism constituting a part of the printing tabulator.

Fig. 2 is an end elevation of the printing 55 carriage showing one position of the parts.

Fig. 3 is a similar view, parts being broken away showing a different position of the parts.

Fig. 4 is a fragmental end elevation showing parts of the paper feeding mechanism 60 and the release of the same.

Figs. 5 and 6 show sections taken respectively through the platens and feed roller.

The invention herein relates to a printing 65 tabulator which is adapted to be actuated by perforated cards, which in their passage through the machine operate elements for setting up type commensurate with the designations on the card and actuate an accumulating mechanism for accumulating 70 therein the data recorded on the card perforations whereby the total accumulated data may be computed and then printed by the printing elements of the machine.

In said co-pending application there is described a machine which comprises a main frame, a main driving shaft, a card feeding mechanism, a card analyzing mechanism and an upper frame 15 (Fig. 1) on which the accumulating and printing mechanism are mounted.

The cards to be analyzed are disposed in a receptacle and are fed from such receptacle to the analyzing mechanism.

85 Power is suitably transmitted to the cam shaft 17 provided with a plurality of cams from which are operated, as explained in said co-pending application, the various mechanisms of the tabulating machine 19, 90 of which it suffices here to say that these are controlled by the cards fed to the analyzer and operate the type segments 20 so that the type 21 will be positioned to print items and totals, in accordance with the cards 95 analyzed, upon a sheet of paper brought against the type by the printing carriage the paper feeding mechanism of which is now to be described.

The printing carriage, designated generally by reference numeral 28 (Fig. 4), is located on the printer tabulator base opposite the type 21 of the tabulating machine 19.

100 The carriage is supported at opposite ends, on the cam shaft brackets 29 (Figs. 105 2 and 3) and the lever shaft brackets 31 carried on the base plate of the printer tabulator. These brackets are tied together at

their upper part by the tie plates 32 bolted at opposite ends to the upper part of these brackets respectively.

The lever shaft brackets 31 are provided at their upper ends with guide slots 34 in which are received the L shaped carriage supporting brackets 35 provided at their forward ends with anti-friction rollers 36 adapted to reciprocate in the elongated openings 37 of the cam shaft brackets.

The supporting brackets 35 are formed near their rear ends with uprights 38 between the upper ends of which are carried the rail supporting bar 39. Between the rear ends of said supporting brackets is carried the arm supporting shaft 40, intermediately of the ends of which are carried the L shaped supporting members 42 comprising the forwardly extending carriage supporting arm 44.

Intermediately of the ends of the supporting bar 39 are carried the forwardly projecting plates 45 which carry at their forward ends the carriage rail 46.

The carriage proper comprises end plates 47 held spaced apart by the tie rod 48 and the bracket shafts 49. On the bracket shafts are mounted the rearwardly extending supporting brackets 50 each provided with a circular opening adapted to receive the carriage rail 46 this opening being provided with a rearwardly extending slot 51 adapted to provide a passage for the plates 45 when the carriage is slipped on to the carriage rail. When the carriage has been put in place it is thus supported by said carriage rails and by the forward ends of the arms 44 engaging under the tie rod 48 at the lower forward part of the carriage.

Between the end plates 47 is mounted the paper roller shaft 60 carrying part of the paper supporting and feeding mechanism to be described more in detail hereafter.

The forward edges of the uprights 38 are each provided with an ear 61 to which is secured a bar 64 to which are secured brackets 68 secured to the bracket shafts 49 connecting the end plates.

The printing is accomplished by the forward movement of the paper supporting mechanism which movement brings the paper against type 21 of the type sectors. This is accomplished by means of the upper and lower carriage actuating levers 87 and 88 (Fig. 3) pivoted on the lever shaft 89 carried by lever shaft brackets 31. The upper and lower actuating levers are both pivotally mounted on said shaft 89 which when printing takes place are suitably locked together, and are oscillated by means of the engagement of the cam roller 90 engaging in the cam groove 91 of the printing cam 92 carried on the cam shaft 17. The actuating levers give one complete cycle of

oscillation once for every revolution of the cam shaft 17.

Now will be described the means for supporting the paper on the carriage.

On the paper roller shaft 60 journaled in the end plates 47 (Figs. 4 and 6) are disposed a plurality of paper rollers 118 each provided with a boss 119 held spaced apart by means of spacing bushings 120 (Fig. 5). Between adjacent pairs of the paper rollers and loosely engaging said bushings are disposed platen support brackets 121 held against rotation by means of the bracket shaft 122 passing through perforations in the lug 123 on the upper part of said brackets, said brackets being held in spaced relation by means of sleeves 124 (Fig. 6) carried on said shaft 122. The lower part of each platen support bracket carries a forward projection 125 on which is secured as by means of a screw 126, the platen support 127 having a recess in its forward end in which is carried the elastic platen block 128 of rubber or other suitable material.

The bushings 120 hold the paper rollers out of frictional contact with the platen brackets. The bushings and the paper rollers and all the parts rotatable on the paper roller shaft 60 are caused to rotate with said shaft by means of frictional engagement with each other brought about by the clamping of the screw 129 (Fig. 3) on said shaft.

Between each adjacent pair of paper rollers are the upper and lower inner paper shields 130 and 131 (Fig. 5), which form a continuation of the cylindrical surface of the paper rollers. These shields have angular extensions 134, each extension having inwardly turned ears 135 each provided with an opening receiving the bracket shaft 122. The upper inner shield 130 is pivotally supported on said rod by said ears, being permitted to move pivotally because of the rounded upper face 136, whereby access may be had to the screw 126. This upper shield 130 may be omitted if desired.

Partly surrounding or housing the lower inner shields 131 and the lower part of the paper rollers 118 are the outer paper shields 137 provided with edge flanges 138 on which are formed turned ears 139 provided with openings receiving the bracket shafts 29 (Figs. 3 and 5). These outer shields cooperate with the lower inner shields 131 to form guides for the paper 140 on which the tabulations are to be printed, the outer shields being continued upwardly in front of the paper rollers 118, whereby are formed extensions 144 (Fig. 5) between which the type of the type sectors pass when the paper is pressed against them by means of the platen blocks 128.

On the lower part of the flanges 138 are

formed small ears 145 provided with perforations in which are carried release arm shafts 146 (Figs. 4 and 5) on which are pivotally carried the feed roller levers 147 between the outer ends of which are journaled the paper feed rollers 148, said rollers engaging on opposite sides of the lower part of the paper rollers 118, and passing through suitable openings in the lower shields 137. These feed rollers are held in contact with the paper rollers by means of feed roller tension springs 149 secured at opposite ends to the journaled pins 150 of the rollers. The inner ends of the feed roller levers are provided with inwardly pointing fingers 152 engaging over the release rod 154 guided in elongated slots 155 in the end pieces 47 (Fig. 3). When this release rod is raised the feed rollers 148 are moved to the position of the dotted lines of Fig. 4, out of contact with the paper rollers, for permitting the removal of the paper. This raising of the release rod is accomplished by means of release arms 156 mounted on the release arm shaft 157 carried in the end plates 47 and actuated by the release lever 158 (Figs. 1, 2 and 3) adapted to be caught behind the shoulder 159 of the inturned lug 160 on the end plate 47, to hold the rollers in released position.

After each number is printed by the type of the type sectors, it is necessary to feed the paper upwardly one or more spaces. This feeding is accomplished by means of engagement of the teeth of the feed ratchet 161, mounted on the shaft 60 by a two armed feed pawl 162 (Fig. 3) pivotally mounted on the feed pawl lever 164 fulcrumed intermediate as on the stud shaft 165 and driven by the link 166, in turn driven by the drive lever 167 mounted on the feed shaft 168, said shaft being actuated by the actuating arm 169 fixed on said shaft and adapted to come into contact with and be moved by the abutment shaft 170 carried on the abutment shaft bracket 171 pivotally mounted on the tie plates 32. The brackets 171 are limited in their rearward movement by the engagement, with the tie plates 32, of a shoulder 172 formed by the lower edge of the lug 174 laterally turned at the rear edge of said abutment shaft brackets, and is yieldably held at its rearward limit of movement by a spring 175 tensioned between said lug 174 and a lug on the rear part of the shaft tie plate 32.

When the carriage is moved forwardly toward the type sectors the free end faces 176 of the actuating arm 169 engage and push down the abutment shaft 170 against the action of the spring 175 until said end face clears said shaft and permits the shaft and its bracket to be snapped back by the spring 175 until stopped by the shoulder 172. Fig.

3 shows the abutment shaft the instant after it has cleared said end face.

After the printing has taken place and the carriage moved rearwardly, the abutment shaft 170 is engaged by the lower side of the actuating arm 169 whereby said arm and drive lever 167 are raised thus rocking the pawl lever 164 and lowering the pawl 162, thus turning the ratchet 161 one or more teeth depending upon how soon the lower member 177 of the pawl is permitted to engage the teeth.

When it is desired that the ratchet feed only one tooth at a time, the feed limiting lever 178 pivotally mounted on the upper part of the end plate 47 is set in the position shown in Fig. 3, thus preventing the lower member 177 to continue to engage the ratchet teeth after it has moved upwardly a distance of one tooth, since the inclined inner face 179 of said member will be engaged by the feed limiting pin 180 mounted on the lower part of the feed limiting lever.

The feed limiting lever 178 is somewhat resilient and is provided with a pair of depressions 181 either one of which is adapted to be engaged by a single projection on the inner face of the end plate 47, depending upon whether the lever is shifted to the right as shown in Fig. 3, or to the left. This arrangement serves to hold the lever in shifted position.

When it is desired that the pawl feed more than one tooth of the ratchet at a time, the lever 178 is shifted to the left of Fig. 3, thus moving the pin 180 away from the lever 100 pawl member 177 permitting said member to be in engagement with the ratchet teeth during the downward movement of the pawl member for a distance of, for instance, two teeth. If desired, the parts may be so proportioned that three or more teeth may be fed at a time.

In order to prevent the feeding of the carriage more than the desired number of teeth, as when the machine is running at very high speed, the pawl 162 is provided with an overthrow preventing cam 182 adapted to engage between the teeth of the ratchet and the inclined face thereof, whereby the ratchet is prevented from turning an other tooth space after this pawl has ceased to travel in its feeding direction. A spring 184 tensioned between the stop member 182 and the lever 164 yieldably holds the pawl in engagement with the ratchet teeth.

The feeding mechanism is yieldably held in position to feed by means of a spring 185 tensioned between the end plate 47 and a perforated ear on the upper part of the inner end of the arm 167.

In order to hold the ratchet wheel 161 and the parts carried on the shaft 60 in the positions in which they are fed by the pawl, I

provide a detent roller 186 revolvably mounted on one end of the detent lever 187 pivoted to the end plate 47 and drawn by the spring 188 strained between the other end of the 5 detent lever and the lower part of the end plate 47, whereby said roller is yieldably pressed between the teeth of the ratchet and yieldably holds the ratchet in the position to which it is fed.

10 When it is desired to insert, remove or feed the paper entirely independently of the feeding mechanism just described, I provide the mechanism, shown in Fig. 4 comprising the paper feed gear 189 fixed on the paper 15 feed shaft 60 and engaged by the idler gear 190 rotatably mounted on the end plate 47, the idler gear being in turn engaged by the knob gear 191 fixed on the stud shaft 165 rotatably mounted in the end plate 47 and 20 carrying knurled knob 192 by which said shaft and gears may be manually rotated.

While the paper is being fed and during the time of printing, it is desirable that it be firmly held against the platens. This is 25 accomplished by means of a clamping mechanism comprising a clamp bar 193 (Fig. 3) carried between the outer ends of the clamping levers 194 provided with intermediate longitudinal slots 195 loosely receiving the 30 paper feed shaft 60, whereby the paper clamp bar is adapted to move toward and from the paper rollers as well as to revolve with said rollers. The inner ends of the clamp levers are provided with small pins 35 196 received in longitudinal slots 197 in the lower ends of the spring levers 198 intermediately fulcrumed on the end plates 47 and drawn by a spring 199 strained between the upper end of the spring levers and the upper 40 part of end plates 47, whereby the clamp lever 194 is yieldably drawn downwardly and the clamp bar 193 is yieldably pressed against the paper and the paper pressed against the paper rolls 118.

45 This yieldable engagement maintains during the printing and feeding of the paper, but after feeding has taken place, as above described, the releasing pin 200 mounted on the cam bracket shaft 201 comes into contact with the abutment shaft 170 and forces the cam bracket shaft and the cam bracket 50 202 to rock rearwardly whereupon the cam edge 203 forces outwardly the pin 196 and therewith the lever 194 and bar 193 and also 55 rocks said lever in a direction clockwise on Fig. 3 whereupon the bar 193 is moved downwardly over the paper and later takes a fresh grip upon the paper when the clamping lever is released by the cam on the next 60 forward movement of the carriage and moves downwardly under the action of the spring 199.

From the foregoing, the operation of the printing carriage will be easily understood. 65 Paper is inserted in the rear opening be-

tween the outer shields 137 and the inner lower paper shields 131, and the paper rolls 118 turned by means of the knob 192 until the part on which it is desired first to print are opposite the platen blocks 128. The feed 70 75 limiting lever 178 is set for the number of teeth it is desired that the feed ratchet shall be fed.

The tabulating machine is then started in operation as explained in the said copending 75 application and the type is set and the accumulators accumulate. The cams 92 cause the printing levers and the carriage to reciprocate and the printing is effected.

I claim as my invention:

1. In an apparatus of the character described, the combination of a rotatable paper roll; means for rotating the paper roll by increments; and means movable with said roll during said rotation for clamping the 85 paper thereto.

2. In an apparatus of the character described, the combination of a rotatable paper roll; means for rotating the paper roll by increments; means movable with said roll 90 during said rotation for clamping the paper thereto; and means for releasing the clamping means and moving the clamping means in a direction opposite to the direction of said rotation.

3. In an apparatus of the character described, the combination of a rotatable paper roll; means for rotating the paper roll by increments; means movable with said roll during said rotation for clamping the paper 100 thereto; and means for releasing and moving the clamping means, between said increments of rotation, in a direction opposite to the direction of said rotation.

4. In an apparatus of the character described, the combination of a paper roll shaft; a plurality of paper rolls disposed upon said shaft; means for rotating said rolls by increments; a clamping bar disposed substantially parallel to said shaft and adapted to 110 engage all of said rolls; and means for clamping said bar to said rolls during the rotation of the rolls and moving the bar in a direction opposite to the direction of said rotation during the intervals between said increments.

5. In an apparatus of the character described, the combination of a shaft; a rotatable paper roll thereon; means for rotating the paper roll by increments; a clamp bar 120 extending longitudinally on the paper roll; and a pair of clamp levers supporting said clamp bar and adapted to draw the clamp bar against the roll.

6. In an apparatus of the character described, the combination of a shaft; a rotatable paper roll thereon; means for rotating the paper roll by increments; a clamp bar extending longitudinally on the paper roll; a pair of clamp levers between which 130

the clamp bar is supported and provided with slots receiving said shaft; and means yieldably pressing upon the clamp bar for causing the clamp levers to draw the bar against the roll.

5 7. In an apparatus of the character described, the combination of a rotatable paper roll; means for rotating the paper roll by increments; a clamp bar extending longitudinally of the paper roll; a pair of clamp levers between which the clamp bar is supported; means for yieldably pressing the levers for drawing the bar against the roll during said increments of rotation; and 10 means for releasing the bar and moving its backwardly relative to the direction of the rotation of the paper roll, during the time between said increments of rotation.

8. In an apparatus of the character described, the combination of a shaft; a rotatable paper roll thereon; means for rotating the paper roll by increments; a pair of clamp levers at opposite ends of the shaft each provided with a longitudinal slot receiving the shaft; a clamp bar supported between the outer ends of the clamp levers; a pin on the inner end of each clamp bar; a spring pressed lever having a slot receiving said pin; and a cam adapted to engage said 20 pin to push said bar away from said roll and to move the bar backwardly relative to the rotation of the paper roll during the time between said increments.

9. In an apparatus of the character described, the combination of a shaft; a rotatable paper roll thereon; means for rotating the paper roll by increments; a pair of clamp levers at opposite ends of the shaft each provided with a longitudinal slot receiving the shaft; a clamp bar supported between the outer ends of the clamp levers; a pin on the inner end of each clamp bar; a spring pressed lever having a slot receiving said pin; a cam bracket having a cam edge engaging said pin for pushing said bar away from the roll and for moving the bar backwardly relative to the direction of rotation of the paper roll, during the time between said increments.

40 10. In an apparatus of the character described, the combination of a reciprocating carriage; a rotatable shaft carried thereon; a paper roll on said shaft; a feeding means for the paper roll; a pair of clamp levers at opposite ends of the shaft each provided with a longitudinal slot receiving the shaft; a clamp bar supported between the outer ends of the clamp levers; a pin on the inner end of the clamp bar; a cam bracket having 45 a cam edge engaging said pin; an actuating member on said bracket; an actuating arm pivoted on said carriage and operatively connected to the feeding means; a fixed support; and an abutment device carried on said support and adapted to engage said actuat-

ing arm and member as the carriage is reciprocated.

11. In an apparatus of the character described, the combination of a carriage; a feeding means; an abutment carrying part; 70 means for causing relative reciprocation between said part and carriage; an actuating device carried by the carriage and operatively connected to the feeding means; and an abutment carried on said abutment carrying part and adapted to be rendered inoperative when the carriage and part move relatively in one direction, and to actuate the actuating device when the carriage and said part move relatively in the opposite 75 direction.

12. In an apparatus of the character described, the combination of a reciprocating carriage; a paper supporting and feeding means carried on the carriage; an actuating 80 device carried on the carriage and operatively connected to the feed means; and an abutment means adapted to be rendered inoperative when the carriage moves in one direction and to actuate the actuating device when the carriage moves in the opposite 85 direction.

13. In an apparatus of the character described, the combination of a reciprocating carriage; a paper supporting and feeding 90 means carried on the carriage; an actuating device carried on the carriage and operably connected to the feeding means; and an abutment device adapted to contact and operate said actuating device when the carriage is moved in one direction and adapted 95 to be contacted and moved out of the path of the actuating device when the carriage is moved in the other direction.

14. In an apparatus of the character described, the combination of a reciprocating carriage; a paper supporting and feeding means carried on the carriage; a fixed support; an abutment means pivoted thereon and yieldably pressed in one direction; an 100 actuating device adapted to contact said abutment and move it out of the path of the device when the carriage is moved in one direction and to be contacted and moved by the abutment device when the carriage is 105 moved in the opposite direction; and means operatively connected to the feeding means and the actuating device for feeding paper.

15. In an apparatus of the character described, the combination of a reciprocating 110 carriage; a paper roll shaft carried thereon; a paper roll and a ratchet wheel on said shaft; a fixed support; an abutment means movably mounted thereon and yieldably pressed in one direction; means for limiting 115 the movement of the abutment and move it out of the path of said device when the carriage is moved in one direction, and to be contacted and moved by the abutment device when the carriage is moved in the other 120 125 130 direction.

- direction; feeding means engaging said ratchet wheel; and means operatively connecting the actuating device and the feeding means.
- 5 16. In an apparatus of the character described, the combination of a reciprocatory carriage; a paper roll carried thereon; a fixed support; an abutment means pivoted thereon and yieldably pressed in one direction; means for limiting the movement of the abutment means in the opposite direction; an actuating device adapted to contact said abutment and move it out of the path of the device when the carriage is moved in one direction, and to press said abutment means against the limiting means when the carriage is moved in the opposite direction, and then to be deflected by said abutment means; and feeding means operatively connected to the actuating device for feeding the paper roll.
- 10 17. In an apparatus of the character described, the combination of a reciprocatory carriage; a paper roll carried thereon; a pair of fixed supports; an abutment bracket pivoted on each support; an abutment shaft supported between the free ends of said brackets; resilient means for yieldably moving said brackets in one direction; stops 15 for limiting the movement of the brackets in the other direction; an actuating device carried by the carriage and adapted to contact said abutment and move it out of the path of the device when the carriage is moved in one direction, and to press said abutment means against the limiting means when the carriage is moved in the opposite direction, and then to be deflected by said abutment means; and feeding means operatively connected to the actuating device for feeding the paper roll.
- 20 18. In an apparatus of the character described, the combination of a reciprocatory carriage; a paper roll carried thereon; a ratchet wheel fixed on the paper roll; a fixed support; an abutment pivoted thereon and yieldably pressed in one direction; means for limiting the movement of the abutment means in the other direction; an actuating shaft carried on the carriage; an actuating arm carried on said shaft and adapted to be contacted by said abutment means; a drive lever mounted on said shaft; a pawl lever fulcrumed intermediately on said carriage; a pawl pivoted to one end of said pawl lever and engaging said ratchet wheel; and a link connecting the opposite end of the pawl with the free end of the drive lever.

WILLIAM W. LASKER.
